UNITED STATES PATENT OFFICE.

HENRY E. MERRILL, OF AKRON, OHIO.

MACHINE FOR MAKING CROCK-RIMS.

SPECIFICATION forming part of Letters Patent No. 398,640, dated February 26, 1889.

Application filed November 20, 1888. Serial No. 291,362. (No model.)

To all whom it may concern:

Be it known that I, HENRY E. MERRILL, a citizen of the United States, residing at Akron, in the county of Summit and State of Ohio, have invented a certain new and useful Machine for Making Crock-Rims, of which the following is a specification.

My invention has relation to improvements in devices for forming a rim about the upper outer edge of crocks when in a plastic state, the bodies of which have been pressed through an annular orifice, and is an improvement of the invention for which I was granted United States Letters Patent No. 310,706, January 13, 1885.

The objects of my invention are to render and maintain the crock-body accurately round, to prevent it crimping or binding while making the rim, and to turn a perfect rim on each crock of uniform height and at a right angle with the axis of the crock.

My invention consists of the devices illustrated in the accompanying drawings, as hereinafter described and claimed.

In the accompanying drawings, in which similar letters of reference indicate like parts, Figure 1 is a central vertical section of a crock, showing my invention applied thereto, the part inside the crock shown in elevation and the surrounding ring in similar section with the crock; and Fig. 2, a perspective of the outer ring partially opened.

The part of the machine within the crock A consists of a central shaft, B, attached to the center of a disk, C, and passing through the center of a wide-faced pulley or drum, D, which is adjustable thereon by means of a set-screw, d, said disk and drum being of the same diameter as the interior of the crock.

On the shaft B, above the drum D, is journaled an arm, E, bearing at its outer end a pulley, e, having in its face a semicircular groove of the size and shape of the upper half of the desired rim, the inner edge of said pulley being arranged to run close to the outside of a channel in the ring, hereinafter described.

The elements thus far are similar to those shown in the patent before referred to.

Outside the crock is a ring, G, which fits

thereon when closed, and consisting of two semicircular pieces hinged together at one end and provided with a clamp at the other, by which they may be locked. In the inner upper corner of this ring is a channel terminating at the base in a quadricircular groove, g, of the same diameter as the groove in the pulley e. In the upper face are two rods, i, arranged to turn therein and with their upper ends bent at a right angle.

In operation the arm E being removed, the shaft B, disk C, and drum D, properly adjusted, are placed in the green crock, the edge of which is then cut accurately in the plane of the drum D. The open ring G is then placed about the crock, being suspended at the proper height by the rods i, which are turned inward and rest on the drum D until the two halves are locked together and clamp the crock sufficiently to retain themselves thereon, when the rods are turned outward. The arm E is then placed on the shaft B and revolved by the handle F, thereby pressing the soft edges of the crock down until the hub of the pulley e rests on the drum D, forming a complete rim in the grooves of the ring and pulley.

I claim—

1. In a machine for forming rims on earthenware vessels while they are in a plastic state, the combination, with a shaft arranged to stand and be supported in the axis of the vessel and a radial arm carrying a rim-forming wheel arranged to revolve about said shaft, of an opening ring arranged to be clamped about said vessel and having a mold to form the lower part of the rim, substantially as shown and described.

2. The combination, with the cut ring G, having a mold for the lower part of the crock-rim, of the bent rods i, arranged to be turned therein and support said ring, substantially as shown and described.

In testimony that I claim the above I hereunto set my hand.

HENRY E. MERRILL.

In presence of—

C. P. HUMPHREY,
E. W. STUART.
